UNITED STATES PATENT OFFICE.

ROY H. McELROY, OF DAYTON, OHIO, ASSIGNOR TO INTERNATIONAL CLAY MACHINERY CO., OF DAYTON, OHIO, A CORPORATION OF MAINE.

SECTIONAL KILN.

1,264,316.

Specification of Letters Patent. Patented Apr. 30, 1918.

Application filed July 2, 1917. Serial No. 178,281.

To all whom it may concern:

Be it known that I, Roy H. McElroy, citizen of the United States, residing at Dayton, in the county of Montgomery and State of Ohio, have invented certain new and useful Improvements in Sectional Kilns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in sectional kilns of either the tunnel or compartment type. The object of the invention is to provide a new and improved form of communicating or flue arrangement. Another object of the invention is to provide an improved arrangement of bag wall behind which the heat is generated. Other objects of the invention will be referred to in the specification and particularly pointed out in the claims. Referring to the accompanying drawings which illustrate the kiln and modifications thereof, Figure 1 is a longitudinal vertical sectional view through a tunnel kiln as constructed in accordance with my invention. Fig. 2 is a similar view showing the invention applied to a kiln of the compartment type. Fig. 3 is a section approximately on the line 3—3 of Fig. 2. Fig. 4 is a horizontal plan view of the kiln as constructed in Fig. 1, the lower portion being a section on the line 4^a—4^a of Fig. 3, the upper right hand portion being a section on the line 4^b—4^b of Fig. 3, while the upper left hand portion is a section on the line 4^c—4^c of Fig. 3. Fig. 5 is a detail view showing a modified construction of the water smoking flues. Figs. 6 and 7 are plan views showing the various possible arrangements of the water smoking flues. Figs. 8 and 9 are detail views showing a modified construction of the gas ducts. Fig. 10 is a view showing a modified construction of the water smoking flues.

It will be understood that the present invention relates particularly to the bag walls and communicating air flues which may be incorporated in section kilns of any well-known type and which may also be constructed either in a single or double battery

form or *en bloc*. As is well known kilns of this type are provided with a plurality of communicating compartments adapted to receive the ware to be burned. The various compartments are progressively fired, the waste heat from the compartment being fired being conducted to the compartments containing the green ware in front, and receiving air to support combustion from the previously fired and cooling compartments in the rear. The green ware is placed in the kiln in a compartment somewhat in advance of the compartment being fired and the burnt ware is removed from a compartment somewhat in the rear and after the ware has cooled. Referring particularly to Figs. 1, 3 and 4, 1—1 represents longitudinal side walls which support an arched top 2. In a sectional kiln of the tunnel type the arched top 2 is provided with drop arch 3 which, together with the peculiar setting of the brick, which is well known in the art, divides the tunnel into separate compartments or sections. The side walls 1—1 are provided with doors 4 which permit access to be had to the various compartments. Arranged at each side of the compartments and parallel with the walls 1—1 are bag walls 5 behind which the heat is incipiently generated. The bag walls 5 opposite the doors 4 are provided with wickets 32. The bag walls 5 of each compartment are in longitudinal alinement with the bag walls of the other compartments and lie parallel with the direction of fire. The hot gases ascend from behind the bag walls and are deflected downwardly by the arched top 2 and pass through the ware and into the next compartment. This communication may be through flues constructed in the brick in a well-known manner or by flues constructed in the kiln as follows:

The kiln as shown in the drawings is provided with a perforated floor 6 and lying beneath the same is a plurality of lateral air flues 7 which communicate with central draft flues 8. The draft flues 8 connect, through lateral draft flues 34, with a main draft flue and a suitable draft appliance such as a fan or stack (not shown). When the kiln is constructed in the form of a single battery the extreme end sections thereof are connected by a return flue (not shown) in a well-known manner. When the kiln is in the form of a double battery the opposite

end sections of the two batteries are connected by lateral flues (not shown) as is well known in the art. To permit the heated or sulfur gases to pass out of the burnt compartment and into the next compartment to pre-heat the green ware therein the central draft flues 8 are, at each compartment, connected by diagonal flues 9 to side air flues 10 which lie along the inner side of the walls 1—1 of the next section or compartment. Extending upwardly from the flues 10 are air flues 11 which enter the compartments behind the bag walls. The flues 8, 9 and 10, in addition to conducting the heated or sulfur gases to the forward or pre heated sections, also conduct heated air from the cooling section in the rear to the burners of the section being burned. Also discharging into the compartments behind the bag walls are gas ports 12 which may be supplied with gas by any well known gas duct arrangement. The ports 12 discharge into the compartments above the air flues 11 and owing to the fact that the air utilized in supporting combustion has been previously heated it is of lighter weight than the gas and results in a better mixture and a more thorough combustion of the fuel. It is to be understood that both the air used in supporting combustion and the heated air from the burning compartment passes through the perforated floors 6, flues 7, 9 and 10 and air flues 11. In Fig. 2 it is contemplated that the division walls 13 will be made permanent thereby forming a compartment kiln. The construction of the remaining portions of the kilns are, however, identical with those kilns are, however, identical with those above described. The various means for supplying gas to the ports 12 are as follows:

In Figs. 3 and 9 the gas is supplied to the kiln through air ducts 14 which lie beneath the kiln and communicate with the burners 12 by individual ducts 15. This individual communication is controlled by valves 17 which are shown horizontally movable in Fig. 9 and vertically movable in Fig. 3, where a pocket 18 is provided in the side of the kiln to permit access to be had to the valve. In Fig. 8 the gas ports 12 are shown as supplied with gas from main gas ducts 19 located at the top of the kiln and communicating with the ports 12 through individual ducts 20 controlled by valves 21.

Kilns constructed in accordance with my invention may be provided with any well known type of water smoking arrangement such as the following: In Fig. 6, which shows a double series of compartments constructed *en bloc*, a centrally disposed water smoking flue 22 is provided which may be mounted either interiorly or exteriorly to the kiln. When the kiln is constructed in a double battery arrangement the opposite ends of the water smoking flues 22 may be

connected by lateral flues (not shown). The water smoking flue 22 is connected to the various compartments by removable hoods 24 which communicate with the flue 22 and the compartments through openings 25 in the top of the kiln. In Fig. 7, which shows a single battery arrangement, the kiln is provided with side water smoking flues 26 which may be either interiorly or exteriorly mounted in reference to the kiln. The water smoking flues 26 communicate with the individual compartments through removable hoods 24 and openings 25 in the top of the kiln similar to that shown in Fig. 6. In Fig. 5 a construction is shown in which the water smoking flues coöperate with the gas flues 15. In this construction a water smoking flue 27 is mounted at the top of the kiln and is connected with the gas flue 15 by down-takes 28 controlled by valves 29. In Fig. 10 the water smoking flue 27 is provided with independent down-takes 33 which enter the compartments through ports 30 and which are provided with valves 31.

Briefly describing the operation of the kiln, the brick or green ware is placed in the kiln in a compartment in front of the compartment being fired and is removed from the kiln from a compartment in the rear. The air used to support combustion enters the kiln through a door of a compartment in the rear and after passing through the cooling compartments, the burning compartment, the preheating compartments, passes out of the kiln through a stack or other draft appliance. In the operation of the water smoking flues 26, they are connected with a cooling compartment and with a compartment containing green ware through ducts 33. The door of the cooling compartment is broken open to admit air, while the compartment containing the green ware is connected with the draft appliance. The air will pass into the cooling compartment where its temperature will be raised and then through the ducts 33 and flues 26 into the compartment containing the green ware where it will dry the same. The air then passes out of the kiln.

Having described my invention, I claim:

1. A kiln provided with a plurality of sections in longitudinal alinement, bag-walls at each side of said sections forming passage ways for the heated air and the products of combustion, said kiln being provided with longitudinally disposed communicating flues between the various sections, and lateral collective air flues.

2. A kiln provided with a plurality of sections in longitudinal alinement, bag-walls at each side of the various sections forming passage ways for the heated air and the products of combustion, said bag-walls being in longitudinal alinement, and air flues longitudinally disposed and con-

necting the various sections, and lateral collective flues communicating with said longitudinal flues.

3. A continuous kiln provided with side walls and a plurality of sections in longitudinal alinement, bag-walls at one side of said kiln and parallel with one of said walls and forming passage ways for the heated air and the products of combustion, and air flues longitudinally disposed connecting said section, and lateral collective air flues directly communicating with one of said longitudinal flues.

4. A kiln provided with a plurality of sections in longitudinal alinement, division walls in said kiln forming a plurality of compartments, bag-walls in said kiln at each side of the compartments and forming passage ways for the heated air and the products of combustion, and parallel with the longitudinal alinement of the compartments, longitudinally disposed air flues connecting said compartments, and lateral collective air flues communicating with said longitudinal air flues.

5. A kiln provided with a plurality of sections in longitudinal alinement, bag-walls in said sections forming passage ways for the heated air and the products of combustion, said kiln being provided with gas and air ports, longitudinally disposed air flues communicating with said air ports and connecting said sections, a perforated floor for said kiln, lateral collective air flues below said floor, and communicating flues between said lateral flues and said air ports.

6. A kiln provided with a plurality of sections in longitudinal alinement, said kiln provided with gas and air ports, a perforated floor for said kiln, lateral collective air flues beneath said floor, draft flues connected to said lateral flues, and a series of longitudinally disposed communicating flues connecting said draft flues and said air ports, said collective air flues and longitudinally disposed communicating flues being adapted to conduct the products of combustion and the air supporting combustion.

7. A kiln provided with a plurality of sections in longitudinal alinement, bag-walls in said sections forming passage ways for the heated air and the products of combustion, said kiln being provided with gas and air ports, a perforated floor for said kiln, lateral collective flues beneath said floor, side air flues connected to said air ports, and communicating flues between said lateral collective flues and said side air flues.

8. A kiln provided with a plurality of sections in longitudinal alinement, bag-walls in said kiln forming passage ways for the heated air and the products of combustion,

said kiln being provided with gas and air ports, a perforated floor for said kiln, lateral collective flues below said floor, draft flues communicating with said lateral collective flues, side air flues connected to said air ports, and communicating flues connecting said draft flues and said side air flues.

9. A kiln provided with a plurality of sections in longitudinal alinement, bag-walls in said kiln, said kiln being provided with gas and air ports, a perforated floor for said kiln, lateral collective flues below said floor, draft flues communicating with said lateral flues, side air flues connected to said air ports, and diagonally communicating flues connecting said draft flues and said side air flues.

10. A kiln provided with a plurality of sections in longitudinal alinement, bag-walls in said kiln forming passage ways for the heated air and the products of combustion, said kiln being provided with gas and air ports, a perforated floor for said kiln, collective flues lateral to the longitudinal flues of the kiln beneath said perforated floor, a series of longitudinally disposed communicating flues connecting said lateral flues and said air ports, a gas duct beneath the kiln, and ducts connecting said gas duct with said gas ports.

11. A kiln provided with a plurality of sections in longitudinal alinement, bag-walls in said sections in parallel relation and behind which combustion may take place or preheated air may pass, said kiln being provided with gas and air ports, a series of longitudinally disposed communicating flues between said sections, a water smoking flue for said kiln, and said kiln being provided with ducts which connect said water smoking flue with said sections through said gas ports.

12. A kiln comprising a plurality of sections in longitudinal alinement, bag-walls at each side of said kiln arranged in longitudinal relation and forming passage-ways for the heated air and the products of combustion, and a series of parallel and longitudinally disposed communicating flues between the various sections of the kiln.

13. A kiln comprising a plurality of sections in longitudinal alinement, bag-walls at each side of said sections arranged longitudinally thereof and forming passage-ways for air or the products of combustion, and a series of parallel longitudinally disposed communicating flues between the various sections whereby the air supporting combustion is preheated.

In testimony whereof I affix my signature.

ROY H. McELROY.
